UNITED STATES PATENT OFFICE.

LOUIS MANDEL, OF CHICAGO, ILLINOIS.

FILM-ROLL HOLDER.

1,164,835.

Specification of Letters Patent. Patented Dec. 21, 1915.

Application filed October 22, 1914. Serial No. 867,956.

To all whom it may concern:

Be it known that I, LOUIS MANDEL, a citizen of the United States, residing at Chicago, in the county of Cook and State 5 of Illinois, have invented certain new and useful Improvements in Film-Roll Holders, of which the following is a specification.

This invention relates to improvements in film roll holders, or film pack, for holding 10 flexible films when used in ribbon form, whereby the film may be placed in the camera in daylight, and from which holder the film may be fed as needed, when the camera is being used for photographic purposes.

15 A further object is to provide an improved holder of this character having means whereby the film will be protected from the light rays which have a tendency to enter an aperture in the wall of the casing of the 20 holder, and which opening is provided for the purpose of attaching the operating means to the spool.

25 A further object is to provide an improved holder of this character having means for protecting the film as it is drawn out of the holder.

30 A further object is to provide an improved device of this character, which will be simple, durable, light, compact and cheap 35 in construction and effective and efficient in operation.

To the attainment of these ends, and the accomplishment of other new and useful objects as will appear, the invention consists 35 in the features of novelty in substantially the construction, combination and arrangement of the several parts hereinafter more fully described and claimed and shown in the accompanying drawing illustrating the 40 invention and in which

Figure 1 is a vertical sectional view taken on line 1—1, Fig. 2. Fig. 2 is a vertical sectional view taken on line 2—2, Fig. 1, and showing only one of the members of the 45 casing. Fig. 3 is a vertical sectional view of the film roll or spool. Fig. 4 is a vertical sectional view of another form of one of the casing members. Fig. 5 is a view similar to Fig. 1 of a modified form of the invention. Fig. 6 is a detail vertical sectional view of 50 still another form of the invention.

Referring more particularly to the drawing and in the present exemplification of this invention, the numerals 10 and 11 designate 55 opposed casing members in which the film roll or spool is arranged. The film roll

or spool comprises a body 12 having secured to one end thereof a flange 13, and in the forms of the invention shown in Figs. 1 and 3, the opposite end of the body is reduced as 60 at 14 to form a projecting portion, adapted to extend through an opening 15 in the wall of the casing member 10. A flange 16 is provided with an offset portion 17 which is 65 adapted to receive the end of the body adjacent the reduced portion 14 and this offset portion 17 of the flange 16 is provided with an opening 18, through which the reduced portion 14 projects, and both of the flanges 13 and 16 may be secured to the body 70 in any desired or suitable manner.

Supported by the wall of the casing member 10 is a pocket element 19, which is provided with an opening registering with the opening 15 in the wall and this pocket member encompasses the opening and is of a size to receive the offset portion of the flange 16 and the adjacent end of the spool, to substantially fill the pocket and the pocket is 75 closed by the flange 16 of the spool, so that 80 any light rays, which would have a tendency to enter the casing and contact with the film, through the opening 15, will be arrested and a light proof joint will result, thereby protecting the film.

The spool may be rotated, if desired in any suitable manner, and for this purpose and in the present form of the invention, the end of the body 12 is provided with an opening 20 which extends through the reduced portion 14 and a pin 21 extends across the opening.

In order to protect the film at the point where it is drawn out of the casing, there is arranged within the casing an element 22 90 preferably arranged in one corner thereof, and this element is provided with a slot or kerf 23 extending therethrough which registers with an opening 24 in the casing wall and through which opening and slot the 100 film 25 passes as it is drawn from the spool. The walls of this slot or kerf are lined with any suitable soft flexible material, such for instance as velvet or other fabric, and which material not only protects the film but also 105 closely contacts therewith to form a closure for the opening formed by the kerf and the opening 24. The film 25 may be secured to the body of the spool in any suitable manner, such as by means of a spring clip 27.

In Fig. 4, the casing member 28 which corresponds with the casing member 10 is

provided with an outwardly projecting offset portion 29 having an opening 30 therein, and this portion 29 forms the pocket for receiving the end of the spool, similar to the 5 pocket 19.

In Fig. 5, the casing member 10 is provided with the opening 15, and secured to the wall of the casing is an element 31 which is provided with an opening 32 there- 10 through and registering with the opening 15, and the element 32 may be formed on the casing wall in any suitable manner. In this form of the invention, the flange 33 which corresponds with the flange 16 in Fig. 15 1 is shaped to form a laterally projecting portion 34, which extends inwardly with respect to the spool, and this portion 34 is secured as at 35 to the body 36 of the spool so as to form a pocket opening outwardly 20 or toward the wall of the casing member 10. This pocket in the offset portion 34 is provided with an opening 37 therethrough registering with the opening 32 and a corresponding opening 38 on the spool body 36, 25 to receive an actuating element which is adapted to engage the pin 39 passing through the opening 38. With this form of the invention, it will be manifest that the element 31 may be of any desired size or 30 height so as to permit the flange 33 of the spool to stand in any desired position with relation to the wall of the casing member 10, and the light rays will be arrested in this 35 form of the invention as efficiently as in the form shown in Fig. 1.

In Fig. 6 the casing member 40 which corresponds with the casing member 28 is formed in a manner similar to that shown in Fig. 4 with the exception that the offset 40 portion 41 of the casing member 40 is deflected inwardly so as to enter the pocket formed in the offset portion 34 of the flange 33, and the deflected portion 41 is formed integral with the casing member 40 instead 45 of separately therefrom and being attached thereto. If desired and in order to provide an additional security against the entrance of light rays into the casing, a third casing member 42 may be provided as shown in 50 Figs. 1 and 5.

While the preferred forms of the invention have been herein shown and described, it is to be understood that various changes may be made in the details of construction 55 and the combination and arrangement of the several parts without departing from the spirit of this invention.

While in the specification and claims this 60 invention is referred to as being adapted for use with films, it is to be understood that the term film is to be used in its broadest sense and to include any flexible sensitized material in ribbon form.

What is claimed as new is:

1. A film roll holder comprising a casing

embodying separable members, and a spool within the casing, said spool shaped to receive an actuating means at one end thereof, the wall of the casing having an aperture adjacent said end of the spool, said wall of the casing, and said end of the spool, being constructed one with a pocket and the other to enter the pocket, said pocket being of a size greater than the opening in the wall of the casing.

2. A film roll holder comprising a casing, embodying separable members, and a spool within the casing, said spool embodying a body and flanges adjacent the end thereof, one wall of the casing having an opening 70 adjacent one end of the spool, said wall and the flange on the adjacent end of the spool being provided one with a pocket and the other shaped to enter and substantially fill the pocket, said pocket encompassing the 75 opening in the wall of the casing.

3. A film roll holder comprising a casing embodying separable members, a spool within the casing, one wall of the casing being provided with an aperture adjacent 80 one end of the spool, and a pocket connected with the apertured wall of the casing and surrounding the said aperture, said pocket receiving the end of the spool.

4. A film roll holder comprising a casing embodying separable members, a spool within the casing, one wall of the casing being provided with an aperture adjacent 85 one end of the spool, and a pocket connected with the apertured wall of the casing and surrounding the said aperture, said pocket receiving the end of the spool, and being of a size only slightly larger than the spool end.

5. A film roll holder embodying a casing, comprising separable members, a spool therein, said spool embodying a body and flanges arranged at the ends thereof, said flanges being of diameters somewhat greater than the diameter of the body, one wall of the casing having an aperture therethrough, 90 and a pocket connected with the apertured wall and surrounding the aperture, said pocket receiving one end of the spool and being of a size less than the diameter of the adjacent flanged end of the spool.

6. A film roll holder embodying a casing, comprising separable members, a spool therein, said spool embodying a body and flanges arranged at the ends thereof, said flanges being of diameters somewhat greater than the diameter of the body, one wall of the casing having an aperture therethrough, 95 and a pocket connected with the apertured wall and surrounding the aperture, said pocket receiving one end of the spool and being of a size less than the diameter of the adjacent flanged end of the spool, the flange on said end disposed in close proximity to the open side of the said pocket.

7. A film roll holder embodying a casing 100

- comprising separable members, a spool therein, said spool comprising a body and flanges at the ends thereof, one of the flanges shaped to form a pocket having an opening 6 in the bottom thereof, one end of the body seated in the said pocket, the wall of the casing adjacent said end of the spool having an aperture therethrough, and a pocket connected with said wall and surrounding the 10 opening therein, the last said pocket receiving the pocket in the flange and being itself closed by the last said flange.
8. A film roll holder embodying opposed casings having registering apertures there- 15 in, a spool in the casings, an element disposed entirely within the innermost casing and having a film passage way therein register- 20 tering with the aperture in the casing, and a yielding lining in the passage way, said lining being disposed entirely within the innermost casing and on both sides of the film.
9. A film roller holder embodying opposed casings having registering apertures there- 25 in, a spool in the casings, an element disposed entirely within the innermost casing and having a film passage way registering with the aperture in the casing, and a soft fibrous lining in the passage way, disposed entirely within the innermost casing and on both sides of the film.
10. A film roll holder embodying a casing comprising separable members, the lateral wall of one member having an aperture therethrough, and a pocket formed around the aperture and opening into the casing, a spool in the casing having a reduced ex- 35 tremity entering said aperture, and a flange
- on the end of the spool adjacent said ex- tremity, said flange being of a size greater 40 than the diameter of the pocket and being itself provided with a pocket into which the end of the spool body is seated, the last re- cited pocket entering the first recited pocket, and the portion of said flange encompassing 45 the pocket forming a closure for the first recited pocket.
11. A film roll holder comprising a casing embodying separable members, a spool in the casing, the flange on one end of the spool 50 and the wall of the casing adjacent said flange being shaped one to form an open pocket and the other to form a projection thereon entering said pocket, and an opening through the said wall of the casing and the said projection in alinement with the end of the spool.
12. A film roll holder embodying a casing, a spool in the casing, the end of the spool and the adjacent portion of the wall of the 55 casing having alined openings therein, said end of the spool and the casing wall being provided one with a circumferential depression and the other with a projection adapted to enter the said depression, said depression 60 and projection surrounding the said openings in the respective elements.
- In testimony whereof I have signed my name to this specification, in the presence of two subscribing witnesses, on this 20th day 70 of October, A. D. 1914.

LOUIS MANDEL.
